Patented February 14, 1905.

UNITED STATES PATENT OFFICE.

WILLIAM J. DIETRICH, OF NEW YORK, N. Y., ASSIGNOR TO AMERICAN CAN COMPANY, OF NEW YORK, N. Y., A CORPORATION OF NEW JERSEY.

DESIGN FOR AN ADVERTISING-LABEL.

SPECIFICATION forming part of Design No. 37,332, dated February 14, 1905.

Application filed December 31, 1904. Serial No. 239,239. Term of patent 14 years.

To all whom it may concern:

Be it known that I, WILLIAM J. DIETRICH, a citizen of the United States, residing in the borough of Brooklyn, city of New York, in the county of Kings and State of New York, (whose post-office address is No. 11 Broadway, New York city,) have invented a new, original, and ornamental Design for an Advertising-Label, shown in the accompanying drawing, forming a part of this specification.

The figure of the drawing is a plan view showing my new design for advertising-label.

I claim—

The ornamental design for advertising-label, as shown.

WM. J. DIETRICH.
